COSMETIC KIT

David Risberg and Melvin Heiman,
Brooklyn, N. Y.

Application December 3, 1945, Serial No. 632,493

4 Claims. (Cl. 132—79)

1

This invention relates to cosmetic kits and more particularly to the construction of the cosmetic container and the arrangement of the cosmetic materials within the container as herein-after described and claimed.

An object of this invention is to provide a cosmetic kit in which a plurality of cosmetic materials are arranged in a compact container so that each cosmetic unit is equally accessible to the user.

A further object of this invention is to provide a cosmetic kit in which a durable container is provided with a combination of cosmetic materials compactly mounted within said container.

A further object of this invention is to provide a cosmetic container in which the cosmetic materials are mounted or affixed to a central body member that is rotatable within the container.

A further object of this invention is to provide a device of a type described which is extremely simple in construction and which makes a compact kit wherein all cosmetic units are readily carried in a woman's purse.

A further object of this invention is to provide a cosmetic container holding all the necessary cosmetics in their proper relationship so that any one cosmetic unit is readily accessible.

A still further object of this invention is to provide a cosmetic container of the type described in which one or more cosmetic materials may be equally and quickly replaced without affecting the cosmetic materials already mounted within the unit.

A further object of this invention is to provide a cosmetic kit in which all the necessary cosmetics are contained in a compact tightly closed container and in which any one or all cosmetics are easily accessible to the user.

Other objects and advantages will appear in the specification and drawings, and the novel features of this invention will be particularly pointed out in the appended claims.

Fig. 1 is a perspective view of the cosmetic kit,

Fig. 2 is a cross sectional view taken through the longitudinal center of the kit illustrated in Fig. 1,

Fig. 3 is a cross sectional view taken on the line 3—3 of Fig. 1, and

Fig. 4 is a perspective view of the central body member.

Referring to Fig. 1 there is illustrated a cosmetic container 10 which comprises a body member 11 mounted rotatably within an outer shell 12 with two hinged end covers 13 and 14. In addition, a hinged cover 15 is provided in the outer shell 12.

2

Referring to Figs. 2 and 3, the construction and relation of the various parts may be followed in which the cosmetic holder body 11 is rotatably secured within the outer shell 12 and in which the hinged end covers 13 and 14 are shown. The cover 14 is hinged to an end plate 16 and the hinged cover 13 is affixed to an end plate 17. The end plates 16 and 17 are securely affixed to the end faces 18 and 19 of the body 11. The end faces 18 and 19 are provided with equal radii circular ends which provide circular bearing surfaces 20 and 21 on which the outer shell 12 is mounted, thus it is apparent that the body 11 and the two hinged end covers 13 and 14 will be inter-connected and the outer shell 12 will be rotatable with relation to the body and end covers, the outer shell 12 having two end apertures that mate with circular bearing surfaces 20 and 21 of the body 11. As illustrated in Fig. 1, the outer shell 12 is provided with two pivot pins 22 and 23 on which a hinged cover 15 is mounted. Two light springs 24 and 25 are provided to urge the cover 15 towards an open position, while a snap fastener 26 is mounted centrally on the outer edge of the cover 15 to mate with a cut-out portion on the inner face of the outer shell 12 when the cover 15 is closed, thus retaining the cover in a closed relationship with the outer shell 12.

Referring to Fig. 4 and Figs. 2 and 3, the body member 11 is illustrated as having four equal area sides 30, 31, 32 and 33 with circular ends 18 and 19, as already described. A circular bore 34 is provided through the center of the body member 11. It will be noted that the four sides of the body member 11 are provided with a plurality of cavities of various shapes. The side 30 is provided with three equal area circular cavities in which cosmetics may be mounted directly or in which cosmetics mounted in circular trays may be forced into these cavities. Likewise, the side 31 is provided with a square cavity and a large rectangular cavity in which cosmetics may also be directly mounted or also may be mounted in trays and forced into said cavities. The sides 32 and 33 are each provided with equal rectangular cavities in which cosmetics may similarly be mounted. The bore 34 is utilized, as indicated in Fig. 2, by mounting a lip stick 36 which fits within the hinged cover 13. Likewise, a loose powder container 38 may be inserted in the opposite side of the bore 34 so that the sieve or open end faces the hinged cover 14. The open end of the powder container 38 may also be provided with a hinged cover 39 to insure retaining the powder in a tightly sealed container. The hinged cover 14 may be provided with a powder puff 40, as indicated.

Various arrangements of the cosmetics may be made in the body member 11, according to the fancy of the user. However, the drawings now illustrate a preferred form in which a large cake of solid powder compressed into a so called pancake make-up may be mounted in the cavity 41 of side 31, while a sponge is mounted in the cavity 42. Likewise, a mascara brush may be mounted in the cavity 43 of the side 32, while the mascara is mounted in the cavity 44. When a mascara brush is mounted means such as a spring clamp 45, will be provided to clamp or positively hold the brush within the cavity 43. Likewise, a cake of rouge and a puff may be similarly mounted inside 33 in the two equal cavities. In similar fashion eye shadow or powdered perfume may be mounted in the circular cavities 46, 47 and 48 of the side 30. In all instances, the puffs or loose articles shall be retained in their position by a clip or spring to maintain them in their set position when inserted.

Referring to Fig. 1 the hinged cover 15 may have a polished surface 58 or a mirror may be mounted to the surface 59 to provide the necessary reflection for the vanity case.

It is apparent in use that the cosmetic kit 10 may be filled with a plurality of cosmetic materials as already described and, likewise, any and all materials are easily removable for refilling. The container is so constructed that the user may readily position the particular cosmetic to be used. In the event the lip stick is to be used, the hinged cover 13 is opened and the lip stick 37 is easily withdrawn from the bore 34 and the user may open the cover 15 to position the reflector in a readily accessible position. Likewise, if the user desires to use loose powder the hinged cover 14 may be opened and the puff 40 may be removed. The sieve or open end of the container 38 is then opened to apply powder to the puff 40 for use. In similar fashion the user may open the cover 16 and by rotating either of the ends 13 or 14 may position one of sides of the body member 11. A detent 55 may be provided on the inner surface of the outer shell 12 to snap into one of the plurality of detention holding means 56, thus providing a positive stop for each of the sides of the body member 11, thus when a side of the body member 11 is positioned to present the desired cosmetic which, as illustrated in Fig. 1, would be eye shadow or perfume in cake form. Similarly the user may turn either end 13 or 14 to present the pancake makeup or the mascara brush and cake or the rouge and puff.

It is apparent that the construction of the kit, as described, and as illustrated in Figs. 1 through 4, provides all the necessary features of a vanity kit and various modifications or changes may be made without departing from the spirit of this invention and this invention shall be limited only by the appended claims.

What is claimed is:

1. In a cosmetic kit the combination, of an outer casing and an inner rotatable body, said casing being supported on the circular periphery of each end of the body, said casing having a sin-

gle hinged cover, said body extending through said casing at each end thereof, a pair of end plates attached to the circular shaped ends of said body, two hinged covers affixed at either end to the end plates, one on each exposed end of said body, means to hold cosmetics mounted on each of a plurality of faces of said body so that any one face is easily accessible through said single hinged opening.

10 2. In a cosmetic case, the combination of a rotatable body and a casing, said body having two circular ends which support said casing, a hinged cover in said casing to allow access to said body, hinged covers attached to each end of said body to cover same but to allow easy access to said ends, a bore through the center of said body to support a plurality of cosmetic containers, and said body having a plurality of faces provided with means to support a plurality of additional cosmetic containers.

15 3. In a cosmetic kit the combination, of an outer casing and an inner rotatable body, said casing being supported on the circular periphery of each end of the body, said casing having a single hinged cover, said body extending through said casing at each end thereof, a pair of end plates attached to the circular shaped ends of said body, two hinged covers affixed at either end to the end plates, one on each exposed end of said body, means to hold cosmetics mounted on each of a plurality of faces of said body so that any one face is easily accessible through said single hinged opening, and means to rotate said cosmetic carrying body with either end of said body that extends through said casing.

20 4. In a cosmetic case, the combination of a rotatable body and a casing, said body having two circular ends which support said casing, a hinged cover in said casing to allow access to said body, hinged covers attached to each end of said body to cover same but to allow easy access to said ends, a bore through the center of said body to support a plurality of cosmetic containers, said body having a plurality of faces provided with means to support a plurality of additional cosmetic containers, and means to rotatably position any one face of said body under the hinged cover in said casing.
